UNITED STATES PATENT OFFICE.

SPENCER H. GALE, OF NEW YORK, N. Y.

BEVERAGE-SHAKER.

1,094,712.

Specification of Letters Patent. Patented Apr. 28, 1914.

Application filed June 9, 1913. Serial No. 772,475.

To all whom it may concern:

Be it known that I, SPENCER H. GALE, a citizen of the United States, residing in the borough of Manhattan, in the city, county, and State of New York, have invented a certain new and useful Beverage-Shaker, of which the following is a specification.

This invention relates to improvements in devices for mixing and cooling beverages, such as cocktails and the like.

The object I have in view is to produce a device in which the beverage and the ice or other refrigerant will be kept separate; at the same time it can be readily cleansed so as to be kept in a sanitary condition. These and further objects will more fully appear from the following specification and accompanying drawings, considered together or separately.

20 In the drawings, Figure 1 is a longitudinal view, partly in section, of a device embodying my invention; Fig. 2 is a plan view of the same, with the beverage container's cover removed; Fig. 3 is a view similar to Fig. 1, of a modification; and Fig. 4 is a detail view of another modification.

In all of the views like parts are designated by the same reference characters.

Referring to Figs. 1 and 2 which show the preferred embodiment of the invention, the beverage container is indicated by the character 1. This container is preferably made of sheet metal, it is of the typical frusto-conical shape, with a closed bottom and open top. Within the beverage container is the ice container 2. This ice container is removably centered within the beverage container, and is secured thereto by means of a lock 3. The ice container is provided with a removable cover 4. This cover is provided with a flange 5. This flange 5 carries two or more fingers 6, which form one element of the lock 3. The other element of the lock in the embodiment chosen for illustration in Figs. 1, 2 and 4 consists of ears 7—7. These ears are located on the inside of the beverage container adjacent to its upper edge. One or all of the fingers 6 are provided with a stop 8. As shown in

50 Fig. 1, the fingers are made of sheet metal, of a sufficiently elastic nature to be distorted, and to retain their original position when the parts are separated. The fingers are helically inclined, as shown in Fig. 1, the stop 8 being located adjacent to the end which lies lowermost.

By introducing the ice container within the beverage container with the fingers in the spaces between the ears, and then giving the ice container a partial rotation, it 60 will cause the fingers to come into engagement with the lower sides of the ears. As before stated, the fingers being helically inclined and elastic they will exert a yielding pressure upon the under side of the ears 65 and will hence yieldingly force the bottom of the ice container into contact with the bottom of the beverage container. The stops 8 will limit the extent of rotation.

For the purpose of securing the bottom of the ice container in the centered position within the beverage container I provided the bottom of the beverage container with a boss 9, which is adapted to enter a socket 10 in the bottom of the ice container. The 70 cover 4 is secured to the ice container 2 by means of a bayonet joint 11. For the purpose of rotating the ice container and removing it from or placing it in position it is provided with a knob 12. The beverage 75 container 1 is closed by a suitable cover 13. That illustrated in the drawings is identical with that shown in patent of Walter G. Barker, dated October 29, 1912, No. 1,042,751. It is of course to be understood 80 that such particular cover is shown only for the purposes of illustration, and any other cover may be employed. 85

The invention may be modified in many ways. As shown in Fig. 4, the ears 7 instead of being separately formed and attached to the beverage container are struck inward out of the material forming the container. In this modification the bayonet joint 11 is omitted, flange 5 making a sufficiently close engagement with the ice container to hold the cover in place. 90

In the modification illustrated in Fig. 3, the lock 3 consists of a screw socket 14 on the beverage container, engaging with 100 screw threads formed in the bottom of the ice container.

In use, the ice or other refrigerant, is enclosed within the ice container, the latter is then centered and locked within the beverage container, the beverage is then poured within the beverage container and occupies the space between the two containers. A suitable cover is put upon the beverage container and the whole shaken, if necessary. 105 This will agitate the ice and bring the beverage into contact with all parts of the out- 110

side of the ice container, chilling it to the necessary degree. The beverage may then be removed from the beverage container when desired.

5 Among the many advantages of this invention it will be seen that the ice does not come into contact with the beverage, thus serving a sanitary purpose. It also provides for uniformity in the strength of the 10 beverage which is not present in devices in which the ice comes into contact with the beverage, owing to the melting of the former. Another advantage is that the 15 drinks for a party of a number of persons may be mixed at one time, and if there are any delays in arrival of other members of the party their drinks will not become warm or diluted, owing to the lapse of time. A further advantage is that the person who 20 mixes the beverages can mix them in quantities, thus securing uniformity of mixture.

A very important advantage of the invention is its sanitary nature. When the ice container is removed from the beverage container the latter is no more than an open vessel, which may very readily be cleansed. So also the outside of the ice container, which comes into contact with the beverage, may be readily cleansed. There are no 25 closed pockets, chambers of involved shape, or other irregularities which cannot be readily reached with an ordinary cleansing appliance.

In accordance with the provisions of the 30 patent statutes, I have described the principle of my invention, together with the apparatus which I now consider to represent the best embodiment thereof; but I desire to have it understood that the apparatus 35 shown is merely illustrative, and that the invention may be carried out in other ways.

Having now described my invention, what I claim as new and desire to obtain by Letters Patent, is:—

40 1. A beverage shaker which comprises a beverage receptacle, and a separable, self-contained ice receptacle located within the beverage receptacle.

2. A beverage shaker, which comprises a 45 beverage receptacle, a self-contained ice receptacle and means for removably centering the ice receptacle within the beverage receptacle.

3. A beverage shaker which comprises a 50 beverage receptacle, a self-contained ice receptacle and a lock for removably centering the ice receptacle within the beverage receptacle.

4. A beverage shaker, which comprises a 55 beverage receptacle, having one member of a lock, and a self-contained ice receptacle having the other member of the lock, so arranged that when brought together the ice

receptacle will be centered within the beverage receptacle. 65

5. A beverage shaker which comprises a beverage container having inwardly extending ears, and a closed ice container having centering fingers adapted to engage with the ears and lock the ice container within the 70 beverage container.

6. A beverage shaker which comprises a beverage container, having inwardly extending ears, and an ice container which includes a removable cover, said cover having centering fingers adapted to engage with the ears and lock the ice container within the 75 beverage container.

7. A beverage shaker which comprises a beverage container having inwardly extending 80 ears adjacent to the upper edge, and a centering boss at the bottom in combination with the ice container having a centrally located bottom socket to engage with the boss, and carrying fingers to engage with the ears. 85

8. A beverage shaker which comprises a beverage container having inwardly extending ears adjacent to the upper edge and a centering boss at the bottom, in combination 90 with an ice container having a centrally located bottom socket to engage with the boss, and a removable cover carrying fingers to engage with the ears.

9. A beverage shaker which comprises a beverage container, having inwardly extending 95 ears adjacent to the upper edge and a centering boss at the bottom, in combination with an ice container having a centrally located bottom socket to engage with the boss, and a removable cover having fingers to engage with the ears, one of said fingers having a stop to engage with the ears. 100

10. A beverage shaker which comprises a beverage container, having inwardly extending ears adjacent to the upper edge, in combination with an ice container having outwardly extending elastic helically inclined fingers which engage with the ears and centering the ice container and elastically engage it with the bottom of the beverage 105 container. 110

11. A beverage shaker which comprises a beverage container having inwardly extending ears adjacent to the upper edge, and a centering boss at the bottom, in combination 115 with an ice container having outwardly extending elastic helically inclined fingers and a centrally located bottom socket, said fingers engaging with the ears to elastically engage the socket with the boss. 120

This specification signed and witnessed this 5th day of June, 1913.
